UNITED STATES PATENT OFFICE.

GEORGE G. FLOYD AND CLARENCE H. HOWARD, OF ST. LOUIS, MISSOURI,
ASSIGNORS TO AMERICAN STEEL-BODY DOUBLE-BOLSTER CO., OF ST.
LOUIS, MISSOURI, A CORPORATION OF NEW JERSEY.

CAR BODY-BOLSTER.

SPECIFICATION forming part of Letters Patent No 755,290, dated March 22, 1904.

Application filed January 9, 1904. Serial No. 188,395. (No model.)

To all whom it may concern:

Be it known that we, GEORGE G. FLOYD and CLARENCE H. HOWARD, citizens of the United States, residing at St. Louis, in the State of Missouri, have invented a new and useful Improvement in Car Body-Bolsters, of which the following is a specification.

Our invention relates to a double body-bolster for railroad-cars.

10 An ordinary double body-bolster usually comprises two parallel single body-bolsters having top and bottom plates or arch-bars, respectively, with their thimbles and connecting-bolts, a center-plate truss similar in construction to and connecting the two body-bolsters together and having the body-center-bearing casting attached thereto, all the said parts being separate pieces fastened to each other and secured as a whole to the car-sills 15 by bolts, whereby owing to the continual and variable strains to which the parts are relatively subjected by the "working" of the car-body their fastenings are liable to become loosened, which destroys the rigidity of the 20 bolster and necessitates constant inspection and repair.

Our invention has for its object to simplify the construction of the body-bolster, to prevent irregular strain of its parts, and to 25 strengthen the car-body.

The invention consists in substituting for the two separate top arch-bars of the ordinary double body-bolster and for the top arch-bars of the center-plate truss a single integral plate 30 to which the two bottom arch-bars of the ordinary double body-bolster and the bottom arch-bars of the center-plate truss are secured, as hereinafter particularly described and claimed, reference being had to the accompanying drawings, forming part of this specification, whereon—

Figure 1 is a top plan of our improved double body-bolster; Fig. 2, a side elevation thereof as seen transversely to the car-body and showing the car-sills in cross-section; Fig. 3, a vertical longitudinal section through the bolster

transversely to the car-body on line 3 3 in Fig. 1; and Figs. 4 and 5, cross-sections through the bolster longitudinally to the car-body on lines 4 4 and 5 5, respectively, in Fig. 1. 50

Like letters and numerals of reference denote like parts in all the figures.

a represents a suitably-shaped plate, which is preferably made of cast-steel integral throughout and adapted to bear against the car-sills *b b'*. The plate *a* in the present case is preferably formed with two opposite and parallel side pieces 1, which span and bear against the entire series of the car-sills *b b'*, transversely thereto. The side pieces 1 are 60 united to each other at each end by a cross-piece 2, which coincides with and bears longitudinally against the under side of the corresponding outer sill *b*, and by an intermediate cross-piece *c*, the side portions 3 whereof coincide with and bear against the under sides of the two middle sills *b'*, while its remaining portion 3', which is located between the said sills *b'*, is formed in the middle and adjacent portions with an upwardly-projecting pocket 65 4, bearing at its sides against the inner faces of the said sills *b'* and having an inclined and straight top 5, similar in shape to the top arch-bars of an ordinary center-plate truss and hereinafter more particularly referred to. 70

The cross-pieces 2 and *c* at the corners where they unite with the side pieces 1 are strengthened by curved or other suitably-shaped gusset-fillings 6, whereby the plate *a* is prevented from springing transversely under the strains 80 of the car-body to which it is secured by bolts, (not shown,) which pass through the holes 7 therefor in the car-sills *b b'* and plate *a*, as in the ordinary bolster. 75

To the plate *a*, directly beneath and longitudinally with the side pieces 1, which take the place of the top arch-bars of the ordinary double body-bolster, are fixed the bottom arch-bars 8 of the two body-bolsters *d*, respectively, the ends of each arch-bar 8 butting against 85 opposite lugs 9, formed integrally with the plate *a* on its under face adjacent to the end 90

cross-pieces 2. The bottom arch-bars 8 are held at the proper distance from the plate *a* by the usual thimbles 10 and are secured to the plate *a* by bolts 11 and by the usual bolts 5 before mentioned, (not shown,) which pass through the holes 7 therefor in the sills *b b'* and plate *a*.

The bottom arch-bars 12 of the center-plate truss *e*, which connects the two body-bolsters *d* together at the middle and is directly beneath the pocket 4 of the plate *a*, bear at their end portions against the under faces of the side pieces 1, respectively, of the plate *a* and are fixed thereto and to the corresponding bottom arch-bars 8 thereunder of the body-bolsters *d* by bolts 13, which pass through the plate *a* and bars 12 and through the thimbles 14 and bottom arch-bars 8, as shown. The ends of the bars 12 butt against lugs 12', which 20 are formed integrally on the plate *a*.

The bottom arch-bars 12 of the truss *e* are fixed at their middle portion to the top 5 of the pocket 4 (or arched portion of the plate *a*, which takes the place of the top arch-bars in 25 the ordinary center-plate truss,) by bolts 15, which pass through the plate thereat, thimbles 16, and bottom arch-bars 12, and through the center-bearing casting 17, which is thereby secured to the truss *e*, as in the ordinary 30 bolster. By this construction the bottom arch-bars 8 of the two body-bolsters *d* and the bottom arch-bars 12 of the center-plate truss *e* instead of being, respectively, fixed to two separate top arch-bars, as in the ordinary double body-bolster, are fixed to a single rigid 35 plate having a solid foundation and extended bearing-surface over a considerable area of the car-sills *b b'*, so that the springing or torsional strain thrown by the working of the 40 car-body on the two separated body-bolsters is taken by the plate *a* without affecting the other parts of the bolster, the rigidity of which is thereby maintained, and by making the plate *a* integral the car-body strengthened. 45

The plate *a* is formed at each end on the under side of the cross-pieces 2 with preferably integral lugs 18, to which the ends of the truss-rods (not shown) are coupled.

f represents the side-bearing trusses, which 50 are fixed at their ends to the side pieces 1 of the plate *a* and act as a brace thereto.

What we claim as our invention, and desire to secure by Letters Patent, is—

1. In a car body-bolster of the class described, the combination of a plate adapted to 55 bear against the car-sills and having two opposite lugs under each side portion thereof, and having an upwardly-projecting pocket, an arch-bar dependent from and fixed to the plate at each side portion thereof transversely to the 60 car-sills, and between the said lugs, a truss consisting of two bottom arch-bars extending between and fixed at their ends to the said bars dependent from the plate, and to the corresponding side portions of the plate thereover 65 respectively, and having their middle portions fixed to the top of the said pocket, a center-bearing casting fixed to the truss, and means for securing the plate to the car-sills, substantially as described and for the purpose set 70 forth.

2. In a car body-bolster of the class described, the combination of a plate consisting of two opposite side pieces, and of cross-pieces 75 uniting the side pieces, the said pieces being adapted to bear against the car-sills and having lateral gussets at their junction to each other, each side piece having two opposite lugs on its under face, and one of the said cross-pieces having an upwardly-projecting pocket, 80 all the said parts being integral throughout, an arch-bar dependent from and fixed to the plate at each side piece thereof transversely to the car-sills and between the said lugs, a truss consisting of two bottom arch-bars 85 extending between and fixed at their ends to the said bars dependent from the plate, and to the corresponding side pieces of the plate thereover respectively, and having their middle portions fixed to the top of the said pocket, a center-bearing casting fixed to the truss, and means for securing the plate to the car, substantially as described. 90

In testimony whereof we have signed our names to this specification in the presence of 95 two subscribing witnesses.

GEORGE G. FLOYD.
CLARENCE H. HOWARD.
